UNITED STATES PATENT OFFICE

LUTHER CHASE BALDWIN, OF PROVIDENCE, RHODE ISLAND, ASSIGNOR, BY MESNE ASSIGNMENTS, TO U. S. BOBBIN & SHUTTLE COMPANY, 1929, OF PROVIDENCE, RHODE ISLAND, A CORPORATION OF RHODE ISLAND

SPOOL OR BOBBIN

Application filed September 15, 1927. Serial No. 219,621.

This invention pertains to spools or bobbins such as are commonly used in textile mills for holding rovings, yarns, or thread and to spools or bobbins of that type in which the 5 barrel and head of the spool or bobbin are independent, the invention relating more particularly to means for securing the head of the spool in assembled relation to its barrel and to a process of making such spools or 10 bobbins.

While a wooden barrel is desirable in spools of this character, on account of its light weight and relative cheapness, the fiber head has, to a large extent, displaced the older 15 wooden head by reason of its greater strength, freedom from splitting, nicking or warping, and on account of its smooth surface which will not abrade fine and delicate yarns. While the fiber head is desirable, its inherent 20 characteristics, and particularly its hardness and usual lack of thickness in an axial direction, makes it difficult to secure it firmly to the wooden barrel and particularly so that it will not turn relatively to the barrel, such 25 relative movement, if permitted, resulting in rapid wear and consequent loosening of the parts and in snarling the yarn or pinching it in the crevice which soon appears between the head and the barrel.

30 In accordance with the present invention I provide simple, cheap, effective and reliable means for holding the spool head in fixed assembled relation to the barrel, the completed spool having a smooth and finished 35 surface free from projections or other elements which might catch in, or injure the yarn and I have devised a simple and practical method of making this improved spool or bobbin.

40 In the accompanying drawings I have illustrated a preferred embodiment of the invention, together with certain of the steps employed in preparing it and I have also illustrated certain desirable modifications of the preferred construction.

In the drawings

Fig. 1 is a side elevation of a completed 45 spool or bobbin embodying my invention; Fig. 2 is a fragmentary end elevation, to

larger scale, of the completed spool as shown in Fig. 1;

Fig. 3 is a fragmentary elevation, partly in radial section, illustrating details of the barrel of the spool;

Fig. 4 is a radial section illustrating a plug or bushing employed for holding the barrel and head in assembled relation;

Fig. 5 is an end elevation of the head of the spool;

Fig. 6 is a fragmentary edge elevation of the head, to larger scale, and partly in section on line 6—6 of Fig. 5;

Fig. 7 is a fragmentary side elevation, partly in section, on line 7—7 of Fig. 2, showing the completed spool;

Fig. 8 is a fragmentary section similar to Fig. 6 but showing a modified construction of head;

Figs. 9, 10 and 11 are views similar to Fig. 8 but showing further modifications;

Fig. 12 is a fragmentary end elevation of a completed spool having a head of the type illustrated in Fig. 9; and

Fig. 13 is a cross-sectional view similar to Fig. 7 but showing a modified form of the invention.

Referring to the drawings, the spool comprises a barrel 1 having heads 2 attached to its opposite ends. Although I herein refer to this barrel as being made of wood, which is a common, cheap and desirable material for the purpose, I contemplate that other materials having the proper characteristics may be employed, such for example, as artificial wood, paper, paper board or metal, and when I refer to wood as the substance of the barrel I wish this to be understood as illustrative only and not as restrictive of the invention.

The barrel 1 is preferably tubular, having an axial bore 3. In accordance with the present invention I prefer to make this bore 3 of larger diameter than that necessary to receive the spindle or other supporting means with which the spool is intended to cooperate.

I prefer to provide at each end of the barrel a part 4 of reduced diameter as compared with the body of the barrel, the reduced portion 4 extending inwardly from the end 5 of

the barrel and terminating at a radial shoulder 6. The length of the portion 4 is preferably substantially equal to the thickness of the head to be employed with the barrel, although it may be slightly different if desired.

The head 2 consists of an annulus of suitable material and of the necessary thickness to provide the strength requisite for the particular use to which the spool is to be put. I have herein referred to this head as being made of hard fiber which is commonly employed for the purpose but I contemplate that other materials may be substituted among which may be mentioned hard rubber, various phenol condensation products, cellulose derivatives, and the like, as well as wood, and while I have referred to fiber as the substance which I use in making the head, I wish it to be understood that this term is used merely by way of example and not as restrictive of the invention.

The head 2 may be stamped or died from sheet material of suitable thickness and may have its outer edges smoothed and rounded and its faces finished if necessary before assembling with the barrel. The head 2 is provided with a central aperture 7 and preferably, though not necessarily, this aperture tapers in diameter from the outer surface 8 of the head toward the inner surface 9 of the latter. Preferably the smaller diameter of the aperture 7 is adapted to receive the reduced end portion 4 of the barrel with a fairly snug fit although an accurate or close fit is not necessary.

The wall of the aperture 7 is provided with one or more recesses 10. While I contemplate that a single recess may serve the purpose I prefer to employ a plurality of such recesses spaced circumferentially a substantial distance apart and preferably I arrange these recesses symmetrically. As here shown, I provide six such recesses, although, as above stated, the exact number is immaterial. These recesses may be formed in any desired manner as, for example, by the use of a file, saw, grinding wheel or other implements, and as shown in Fig. 6 these recesses extend from the outer surface 8 of the head part way across the thickness of the head, the recesses tapering in width and depth and being of substantially triangular cross section. Such spaced recesses as I have described may be formed much more readily than teeth or projections jutting out from the wall of the aperture since the formation of such teeth or projections necessitates a molding or similar manipulation of the fiber head during its process of manufacture or the cutting away of a very substantial portion of the intervening material.

Having provided a barrel and head as described, I now also provide a plug or bushing 11 as shown in Fig. 4. This plug 11 pref-

erably comprises a cylindrical body portion 12 adapted to fit snugly within the bore 3 of the barrel and a head or wedge portion which flares outwardly from the body 12, this wedge portion 13 preferably terminating in a smoothly rounded outer end surface 14 adapted to give a desirable finish to the completed spool. Preferably this plug or bushing 11 is provided with an axial bore 15 of a suitable diameter to fit over the spindle or other support upon which the spool is intended to be mounted.

In assembling the parts thus described, I place the head 2 over the reduced end portion of the barrel, causing the inner face 9 of the head to bear against the shoulder 6. I then insert the plug or bushing 11 in the bore 3 of the barrel, preferably first coating the outer surfaces of the plug with a suitable adhesive, for example, hot glue. The cylindrical body 12 of the plug is inserted in the bore 3 and then the plug is driven forcibly inward so that its flaring wedge portion 13 expands the material at the end of the barrel, (constituting the reduced portion 4 thereof,) into firm contact with the inner wall of the aperture 7 in the head, as shown in Fig. 7. In this figure the expanded and outwardly flaring portion of the barrel is indicated at 4^a. In thus forcibly expanding the portion 4 of the barrel, its substance is caused to protrude into the recesses 10, as indicated at 4^b in Figs. 2 and 7. The engagement of these integral portions of the material of the barrel with the recesses in the head provides positive means for preventing relative rotation of the head and barrel. At the same time the adhesive uniting the plug 11 to the barrel binds all of the parts together so that it is thereafter impossible to separate them, except by breakage, the head being firmly retained between the shoulder 6 of the barrel and the overlapping flaring portion 4^a of the barrel.

While I have referred to the use of adhesive in securing the plug 11 in position, I wish it to be understood that other fastening means might be employed if desired and when in the claims I have referred to fastening means I wish this term to be construed broadly and not as necessarily limited to glue or other adhesive.

While the type of recess above described is desirable and easy to make, I contemplate that other types of recess may be found useful and desirable under certain conditions. For example, in Fig. 8 I have indicated the head 2^a as provided with the aperture 7^a and in this arrangement I show substantially straight recesses or grooves 10^a of uniform width extending from the outer surface of the head across to its inner surface. Such recesses may be spaced apart in the same way as the recesses 10 above referred to and may be made by the use of any suitable implements or in any desired manner.

In Fig. 9 I illustrate an arrangement of recesses of somewhat different character, the head 2^b having the central aperture 7^b and the recesses 10^b in the wall of this aperture. In this instance the recesses 10^b extend from the inner face 9^b of the head toward its outer face 8^b but terminate before they reach the outer face. Thus, the edge 16 of the aperture 7^b at the outer face 8^b of the head is smooth and unnotched. The recesses 10^b may be of 10 triangular section or of such other form as may be desired.

In Fig. 10 I have shown a further modification in which the head 2^c is provided with the central aperture 7^c and with a series of recesses 10^c in the wall of the aperture. These recesses are of substantially diamond shape and lie wholly within the thickness of the head so that both edges of the aperture 20 (at the opposite faces of the head) are smooth and unnotched.

In Fig. 11 I show a still further modification in which the head 2^b has the central aperture 7^d whose wall is furnished with a series 25 of substantially circular or semi-spherical recesses 10^d.

When heads of the types shown in Figs. 9, 10 or 11 are assembled with the barrel and secured in position by means of the plug or bushing, as above described with respect to Figs. 1 to 7, the reduced portion 4 of the barrel is expanded and flared outwardly in the same way as indicated in Fig. 7 to provide a ring-like portion 4^a which appears at 30 the end of the spool, but as shown in Fig. 12 those portions of the material of the barrel which are forced outwardly into the recesses in the head do not show from the exterior so that in the completed spool these retaining 35 elements are not apparent. The arrangements shown in Figs. 9, 10 and 11 are intended merely as examples of structures in which the retaining elements are concealed in the completed spool and obviously other shapes 40 of recess than those illustrated could be employed for the purpose, and I regard all such shapes as within the scope of the invention.

Fig. 13 illustrates another form of the invention, in which the material of the plug 111 is pressed directly into engagement with the annular head 102. As in other forms of the invention, the head may have a central aperture which is tapered from the outer surface 108 of the head toward its inner surface 109, 55 and the wall of the aperture may have a plurality of recesses 110. In the form of the invention disclosed in Fig. 13 the material of the bushing 111 is forced into direct engagement with the tapered wall of the head 60 102 with protuberant portions 104^b thereof engaging recesses 110 to hold the head to barrel 101.

While I have shown certain desirable modifications, I wish it to be understood that these 65 are not in any sense to be regarded as restric-

tive of the invention but merely as suggestive of further possibilities in the way of modification of the structure which I have herein claimed broadly and I wish it to be understood that further changes in shape, size, relative proportions and arrangement of parts, and materials used may be made as circumstances may warrant and within the scope of the appended claims.

I claim:

1. A spool or bobbin comprising a tubular barrel and a head independent thereof, the head having a central aperture receiving the end portion of the barrel, the wall of said aperture having circumferentially spaced recesses and the barrel having integral projections engaging said recesses whereby positively to prevent relative rotation of the head and the barrel, said recesses being spaced from the outer surface of the head and tapering in width, being widest adjacent to said inner face of the head.

2. A spool or bobbin comprising a wooden barrel and a hard fiber head, the head having a central aperture receiving the end portion of the barrel, the wall of said aperture having circumferentially spaced recesses and the barrel having integral projections engaging said recesses whereby positively to prevent relative rotation of the head and barrel, said recesses and projections being wholly concealed from view in the completed spool.

3. A spool or bobbin comprising a barrel and a head independent thereof, the head having a central aperture receiving the end portion of the barrel, the wall of said aperture having circumferentially spaced recesses and the barrel having integral projections engaging said recesses whereby positively to prevent relative rotation of the head and barrel, the recesses tapering in width and being widest adjacent to the inner face of the head and terminating at a point spaced from the outer face of the head, said recesses and projections being wholly concealed from view in the completed spool.

4. A spool or bobbin having a tubular barrel and a head independent of the barrel, said head having a central aperture provided with a recess in its wall, the recess being spaced from the outer surface of the head, the barrel comprising an end portion of reduced diameter disposed within said aperture, said end portion having a projection entering said recess, and a bushing disposed within the end of the barrel, said bushing holding said end portion of the barrel in firm engagement with the head.

5. A textile spool or bobbin having a tubular wooden barrel and a hard fiber head, said head having a central aperture provided with widely spaced recesses in its wall, said recesses being spaced from the outer surface of the head and being of substantially triangular cross section, the barrel having an end

- portion disposed within the aperture within the head, and a wooden plug disposed within the barrel and secured thereto by means of adhesive, said plug having a tapered portion 5 forcibly inserted in the end portion of the barrel so as to embed the material of the barrel in the spaced recesses in the head, thereby to prevent relative rotation of the head and the barrel.
- 10 6. A spool or bobbin comprising a barrel having an axial bore, a head independent of the barrel, said head having a central aperture provided with spaced recesses in its walls, said recesses being spaced from the 15 outer face of the head, the barrel having an end portion disposed within the aperture in the head, a plug having a body portion fitting into and fixed within the bore in the barrel and having a tapered head acting as a wedge 20 to hold the end portion of the barrel in firm engagement with the wall of the aperture in the head and to force portions of the material of the barrel into said recesses.
7. A spool or bobbin having a tubular 25 wooden barrel and a hard fiber head, the head having a central aperture which tapers from its outer surface inwardly and which has recesses in its wall, the barrel comprising an end portion of reduced diameter providing 30 a shoulder for engagement with the inner surface of the head, said reduced end portion being disposed within the aperture of the head and flaring outwardly into contact with the wall of the aperture, portions of the material of the barrel entering the recesses in 35 said wall to prevent relative rotation of the barrel and head, said portions being concealed from view in the completed spool, a bushing disposed within the end of the barrel, said bushing having a tapered part engaging the flaring end portion of the barrel, and means fixedly securing the bushing within the barrel.
8. That method of making spools or bobbins which comprises as steps preparing a 45 barrel having an axial bore and an end portion of reduced diameter terminating in a radial shoulder, preparing a head having a central aperture adapted to fit over the reduced end portion of the barrel, said aperture tapering in diameter from the outer toward the inner face of the head and having a plurality of circumferentially spaced recesses in its wall, said recesses being spaced 50 from the outer surface of the head, preparing a plug having a body portion adapted to fit snugly within the bore in the barrel and a flaring wedge portion, pushing the reduced end portion of the barrel into the aperture 55 in the head until the shoulder engages the inner face of the head, and driving the plug into the bore in the barrel until its flaring wedge portion expands the end of the barrel outwardly into contact with the tapering 60 wall of the aperture in the head and causes 65 the material of the end portion of the barrel to protrude into said recesses.
9. That method of making spools or bobbins which comprises as steps preparing a wooden barrel having an axial bore and an end portion of reduced diameter terminating in a radial shoulder, preparing a hard fiber head having a central aperture adapted to fit over the reduced end portion of the barrel, 70 said aperture tapering in diameter from the outer surface of the head inwardly and having a plurality of circumferentially spaced recesses in its wall, said recesses being spaced from its outer face, preparing a hard wooden plug having a body portion adapted to fit snugly into the bore in the barrel and an outwardly flaring wedge-like end portion, pushing the reduced end portion of the barrel into the aperture in the head until the shoulder engages the inner face of the head, applying 75 adhesive to the outer surfaces of the plug, and driving the plug into the bore in the barrel until its flaring wedge portion expands the end portion of the barrel outwardly into close contact with the tapering wall 80 of the aperture in the head and causes the material of the end portion of the barrel to project into said recesses.
